HENRIETTE B. WOEHRLE, OF NEWARK, NEW JERSEY, ASSIGNOR TO THE SINGER
MANUFACTURING COMPANY, A CORPORATION OF NEW JERSEY.

SEWING-MACHINE ATTACHMENT.

988,528.

Specification of Letters Patent. Patented Apr. 4, 1911.

Application filed May 18, 1909. Serial No. 496,821.

To all whom it may concern:

Be it known that I, HENRIETTE B. WOEHRLE, a citizen of the United States, residing at Newark, in the county of Essex 5 and State of New Jersey, have invented certain new and useful Improvements in Sewing-Machine Attachments, of which the following is a specification, reference being had therein to the accompanying drawings.

10 This invention relates to an improvement in that class of sewing machine attachments designed for sewing strips of fabric into a turned tubular trimming with the stitched portion inturned to conceal the stitching; 15 and the invention has for its object to provide a simple and effective attachment of this class which may be readily applied to the machine without special fitting.

The invention consists in the attachment 20 herein shown and described and set forth in the appended claims.

In the accompanying drawings, Figure 1 is a perspective view of the forward portion of the sewing machine with a presser-foot 25 embodying the present improvements. Fig. 2 is a perspective view taken from above the rear of the attachment, and Fig. 3 a similar view from the lower side of the attachment. Fig. 4 is a longitudinal section through the 30 tubular arbor of the attachment and the throat-plate of the sewing machine and representing the relation of the feed-dog to the foot-plate of the presser-foot, and Fig. 5 a transverse section of the same representing 35 the attachment in front end view. Fig. 6 is a transverse section through the foot-plate and representing the strip-guiding portion of the attachment in front end view. Fig. 7 is a perspective view showing a portion of 40 the turned tubular trimming produced by the attachment.

The portions of the sewing machine represented in Fig. 1 comprise the usual bed-plate 1, throat-plate 2 and slide-plate 3, with 45 the lower part of the head of the bracket-arm 4 in which are journaled the reciprocating needle-bar 5 carrying the needle 6 and the presser-bar 7 having upon its lower end the collar 8 provided with the usual seat 9 upon which is secured by means of the fastening screw 10 the slotted shank 11 of the presser-foot formed with the flat foot-plate 12. The foot-plate has a reduced forward extension provided with the laterally projecting supporting arm 13 affording a notch 50

14 in front of its body portion, while the edge of the foot-plate has a needle-clearance notch 15.

To the arm 13 is rigidly connected by means of the lateral fin or plate 16 the front 60 end portion of the tubular arbor 17 which has a bore of uniform size, but whose opposite end is formed with an annular enlargement 18 to afford a rounded extremity over which the strip of material previously 65 stitched into tubular form may be drawn into the end of the arbor toward the front of the machine. The front end of the arbor 17 is surrounded by a scroll 19 having laterally extending spaced parallel members 20 70 attached to or merged into the lateral supporting arm 13 of the foot-plate 12.

By reference to the drawings it will be seen that the forward portion of the presser-foot provided with the arm 13 is slightly 75 upturned whereby the scroll is elevated above the bearing surface of the presser-foot in relation to which it is slightly inclined, and the tubular arbor 17 is curved in the direction of its length so that, while its receiving end is inclined similarly to the surrounding scroll, its delivery end is substantially parallel with the operative face of the presser-foot, as indicated more particularly 80 in Fig. 4. The tubular arbor is arranged 85 parallel with and close to the adjacent edge of the foot-plate 12 so as to afford, in the present instance in conjunction with the needle-clearance notch 15, a narrow slot 90 which constitutes a needle aperture, the arbor extending from the supporting arm 13 backwardly beyond the operative or work-engaging face of the foot-plate 12 so as to receive in its central aperture the stitched 95 margin of the strip after it emerges from between the presser-foot and the feed-dog by which the work is propelled for the stitching operation. To insure the proper introduction beneath the presser-foot of the overlapped marginal portions of the strip confined 100 between the parallel members 20, the scroll is terminated in front of the body portion of the foot, and the marginal portions of the tape are led therefrom through the notch 14 and beneath the operative portion of the foot-plate, the scroll 19 being disposed entirely above the level of the lower or operative face of the presser-foot to avoid 105 interference with the latter's normal action upon the work. 110

It is of considerable importance in the practical operation of the attachment that the operative relation of the tape-guiding parts and the foot-plate be rigidly maintained in closely spaced relation, so that they will rise and fall together under the action of the feed-dog, as any relative movement of these parts which would result from mounting them independently would cause 10 the overlapped marginal portions of the strip to be drawn laterally more or less from beneath the foot-plate and then crowded into the slot intermediate the edge of the same and the arbor 17 so as to produce uneven 15 and otherwise imperfect work. According to the present improvement the parts are so arranged that the fabric is controlled to the fullest extent from the time it enters the attachment until it emerges therefrom as a 20 finished trimming.

Projecting from the scroll 19 longitudinally of the arbor 17 and inwardly toward the latter are two drag-springs or tension arms 21 22 having their operative ends 25 curved to conform substantially with the exterior of the arbor and normally resting yieldingly in contact therewith, being thus adapted to press the fabric closely in contact with the arbor adjacent the stitching 30 point at the needle aperture 15 of the foot-plate 12.

The throat-plate 2 is provided with the usual feed aperture 23 through which passes the usual serrated feed-dog 24 which is disposed directly beneath the foot-plate 12 of the presser-foot with which it co-operates in feeding the overlapped marginal portions of the strip of fabric presented at the side of the arbor 17.

40 In the operation of the attachment, as represented in Fig. 4, the presser-foot is first raised and the strip of fabric is introduced into the substantially annular passage between the front end of the arbor 17 and the scroll 19. The upper marginal portion of the strip is preferably led across the top of the foot-plate 12 to a sewing point marked by the needle aperture 15, after which it is tucked in through the notch 14 by the use of 45 a stiletto by which it is drawn forward through introduction of such implement in the clearance slot afforded between the side of the arbor 17 and the adjacent edge of the foot-plate 12. After drawing the strip in 50 the direction of feed, preferably somewhat more than the length of the arbor 17, the advanced end of the fabric is seized by the hooked end of a threading wire passed through the tubular arbor and is drawn 55 through the latter where its forward end may be grasped by the operator and its delivery through the arbor, while the stitching proceeds, continued in opposition to the direction of feed and of seam formation.

60 65 While the product as thus described com-

prises a mere tube which may be flattened in its application to a body fabric in the form of trimming, and is thus adapted for certain kinds of ornamental uses, it is in practice sometimes provided with a cotton or wool filling which is led into the rear end of the tube at the turning point where it is frictionally drawn into the tubular trimming to afford a soft filling therefor as represented in Fig. 7, where the strip or tape *a* is shown formed in its body portion into a tube *b* with overlapped marginal portions *c* stitched together at the junction with the tubular portion by means of the line of stitching *d*, the tube *b* being turned inside-out at the point *e* 75 over the expanded end 18 of the arbor 17 at which point the filling cord *f* is drawn into the same, the marginal portions *c* being drawn into the interior of the finished article where they are entirely concealed, as is 80 also the line of stitching.

As will be readily seen, the object of the drag-springs 21 and 22 is to yieldingly maintain the fabric in contact with the exterior of the arbor 17 to whose cylindrical surface 90 it is thus caused to closely conform, thereby insuring uniformity of the tubular portion *b* of the trimming cord; but it will be observed that these springs are adapted to yield readily to permit the easy passage of 95 cross seams such as are met at frequent intervals in the bias strips commonly employed in producing this class of trimming.

Having thus set forth the nature of the invention, what I claim herein is:—

1. A sewing machine attachment for producing stitched and turned tubular trimming comprising a presser-foot constructed with a foot-plate having at its forward end a lateral supporting arm, a tubular arbor 105 disposed parallel with one edge of said foot-plate and spaced therefrom, a guiding scroll fixed to said supporting arm and surrounding the forward end of said arbor with which it forms an annular passage to receive and fold a strip of fabric, and drag-springs adapted to press the material upon the exterior of said arbor.

2. A sewing machine attachment for producing stitched and turned tubular trimming comprising a presser-foot constructed with a foot-plate, a tubular arbor rigidly attached to and spaced from one edge of said foot-plate to form a narrow intermediate slot constituting a needle aperture, and a guiding scroll surrounding and spaced from the surface of the forward end of said arbor and terminating in front of said needle-aperture, said scroll being disposed entirely above the level of the lower or operative face 115 of the foot-plate of said presser-foot.

3. A sewing machine attachment for producing stitched and turned tubular trimming comprising a presser-foot constructed with a foot-plate having a reduced for-

wardly extending portion with a laterally extending arm, a tubular arbor parallel with and arranged close to the edge of said foot-plate with its forward end rigidly secured to said lateral arm and its rearward end ex-
tending beyond that of said foot-plate and forming with the latter a narrow slot constituting a needle aperture, and a guiding scroll carried by said lateral arm and sur-
rounding and spaced from the surface of the forward end of said arbor and terminating

in front of the operative or body portion of the foot-plate of said presser-foot, said scroll being disposed entirely above the level of the lower or operative face of the foot-plate. 15

In testimony whereof, I have signed my name to this specification, in the presence of two subscribing witnesses.

HENRIETTE B. WOEHRLE.
